[57] CLAIM

The ornamental design for an insert pad for a diaper or pant, as shown and described.

DESCRIPTION

FIG. 1 is a front elevational view of an insert pad for a diaper or pant, showing my new design;

FIG. 2 is an end elevational view thereof, the opposite end elevational view being identical thereto;

FIG. 3 is a front elevational view thereof, the broken line showing of the diaper is for illustrative purposes only and forms no part of the claimed design;

FIG. 4 is a side elevational view thereof, the opposite side elevational view being identical thereto; and,

FIG. 5 is a rear elevational view thereof.

FIG. 1

FIG. 4

FIG. 5

FIG. 2

FIG. 3
